Primary Examiner — Marcus Jackson(74) *Attorney, Agent, or Firm* — Koppel, Patrick, Heybl & Philpott(57) **CLAIM**

The ornamental design for an LED lamp, as shown and described herein.

DESCRIPTION

FIG. 1 is a perspective view of an LED lamp according to another embodiment of the present invention.

FIG. 2 is a front elevation view of the LED lamp shown in FIG. 5, with the rear and side views being substantially identical in ornamental appearance.

FIG. 3 is a top plan view of the LED lamp shown in FIG. 5; and,

FIG. 4 is a bottom plan view of the LED lamp shown in FIG. 5.

The broken lines shown in FIGS. 1-4 depict environmental subject matter only and form no part of the claimed design in those embodiments.
